BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR WORKING UPPERS OVER LASTS.

1,413,589.

Specification of Letters Patent. Patented Apr. 25, 1922.

Application filed March 5, 1918. Serial No. 220,489.

To all whom it may concern:

Be it known that I, BERNHARDT JORGENSEN, a subject of the King of Denmark, residing at Beverly, in the county of Essex and State of Massachusetts, have invented certain Improvements in Machines for Working Uppers Over Lasts, of which the following description, in connection with the accompanying drawings, is a specification, like reference characters on the drawings indicating like parts in the several figures.

This invention relates to machines for working uppers over lasts, and more particularly to machines for performing such operations on the end portion of a shoe. The invention is shown herein as embodied in a machine having means for pulling an upper over the toe of a last and for working the upper into lasted position and fastening it at the toe; but it should be understood that the invention, in many of its aspects, is not limited to a combination of means for performing these several operations nor to means restricted in utility to toe lasting.

One object of the invention is to provide a machine adapted for operation upon the toe ends of shoes which have been previously side-lasted as, for example, a certain type of shoe in which the upper is made of felt material. In the manufacture of this type of shoe it is the usual practice to cut the upper of sufficient size to permit its lower marginal portion to be extended inward at the bottom of the shoe in such manner as to serve to a greater or less extent as an insole and, before the shoe is mounted on a last, to stitch the bottom edges of the opposite side portions of the upper either directly together or to an insertion of similar ma-

terial extending for a portion at least of the distance lengthwise of the shoe. The upper is then dampened and a last is inserted to stretch and form the material in lasted shape. In accordance with the usual practice and for the best results the bottom edges of the material in the toe portion of the shoe are left free and unsecured until after the last has been inserted, the shoe being then in side-lasted condition, after which this portion of the shoe, while damp, is shaped by a toe lasting operation.

The operation of lasting the toe of such a shoe must be performed with due regard to the peculiar conditions resulting from the preceding steps in the manufacture of the shoe, as well as to the character of the material of which the shoe is made. At the rear of the toe portion where the shoe is already side-lasted the upper is stretched across the last, or laterally, to its final shape, and in a less degree the upper at the sides and over the top of the toe is likewise stretched laterally by reason of its connection to the stretched portion at the rear. At the toe end of the last, however, the upper is in a substantially unstretched condition, and in lasting the toe it is therefore desirable to pull this portion of the upper to some extent over the last. This operation, however, and also the operation of laying the margin of the upper over the bottom of the last, must be so performed as to avoid distorting the previously side-lasted portion of the shoe and also to avoid crowding any portion of the unsecured margin back over the side-lasted portion adjacent to the edge of the last back of the toe. It has been the practise heretofore to grip different portions of the unsecured margin of the upper in succession with hand pincers and to pull each portion so gripped and draw it inward over the bottom of the last and then to drive a tack to secure it in lasted position. In order to flatten the stock down upon the margin of the last at the toe, a plurality of blows are then delivered with a hammer. After the stock has dried and set in permanent shape the tacks are removed, the upstanding edges of the upper at the toe end are trimmed off, and an outsole stitched to the shoe.

The toe lasting operation performed in the manner above described is not only slow but is frequently productive of unsatisfactory results. It is very difficult, in pulling over and securing different portions of the stock in succession, and particularly in pulling the portions at the sides of the toe, to effect uniform lasting and to avoid, on the one hand, distorting the previously side-lasted portions back of the toe and, on the other hand, producing one or more pleats or folds in the stock so pronounced as to ex-

tend out near the edge of the shoe in the portion to which the outsole is to be stitched. Such a fold in the margin near the edge of the shoe is likely to be cut when the up-standing edge of the upper is trimmed off, with a consequent weakening of the portion of the shoe to which the outsole is to be attached. When the shoe is made of felt, moreover, the strength of the felt material frequently varies in different portions, and for this reason and in view of the damped condition of the material there is danger of tearing it by too hard a pull or of rupturing it by the blows delivered over the margin of the last bottom for flattening the margin.

This invention provides a machine which in many respects is particularly adapted for working over a last the toe portion of the upper of a shoe which has been previously side-lasted, such as a felt shoe of the type above referred to, and in this aspect the invention affords automatic means for performing rapidly and uniformly an operation heretofore performed in a comparatively slow and unsatisfactory manner by hand. It will be evident, however, that the invention in many of its aspects is not restricted to use in the manufacture of felt shoes nor to use in the manufacture of shoes previously side-lasted.

Among its more important features the invention provides novel toe lasting means constructed, for the purposes in view, to operate with less effective pressure upon the stock at the sides of the toe than at the end of the toe. A particular advantage of a construction embodying this feature, in operation upon a shoe previously side-lasted, is that the pressure upon different portions of the stock is proportioned to the different respective requirements of the end and the sides of the toe, since portions of the stock at the sides of the toe adjacent to the previously lasted portion are already stretched to some extent by reason of their connection to the lasted portion and therefore require less overworking pressure. A further important advantage in the use of such graduated pressure, moreover, is that displacement of the previously side-lasted portion of the upper is avoided and the toe lasting is rendered uniform with the side lasting.

A further feature of the invention resides in novel means for working the upper over the bottom of a last round the toe constructed to operate with a comparatively large component of movement in a direction or directions laterally of the shoe. In a shoe of the type hereinbefore described the inner edge of the margin of the upper must be gathered within a comparatively small area at the toe end of the shoe, and the portions at the sides of the toe should be worked inward without overlapping the previously side-lasted portion on the margin of the last. In

the construction shown, in which end lasting wipers are employed, the wipers are so constructed and operated as to cause all portions of the wiping edges to have a component of movement laterally of the shoe. The tendency of the wipers accordingly is to work all portions of the margin or the upper inward toward the longitudinal median line of the shoe. Advantageously also the wipers shown are constructed and arranged for operation with diminished pressure at the sides of the toe, thus rendering them particularly effective for the purposes in view in the manufacture of a previously side-lasted shoe, as hereinbefore explained.

Still another feature of the invention resides in a novel combination of means for pulling an upper at the toe end of a last and for working the pulled upper into lasted position. As adapted particularly for use in lasting the toes of shoes which have been previously side-lasted, the machine shown is organized to pull the upper at the end of the toe only and to gather and wipe the margin of the upper uniformly inward round the end and along the sides of the toe. It is also an important characteristic of the illustrated construction embodying this feature, although not essential to the utility of the invention in many of its aspects, that a portion of the margin of the upper of comparatively narrow extent widthwise of the shoe is pulled back from the toe end over the bottom of the last and that portions of the margin at the sides of the toe are worked inward in such manner as to cause the intermediate pulled-back portion to be gathered substantially between the side portions. The novel construction further comprises means for pressing the upper against the toe end of the last to hold it in tensioned condition, permitting the upper to be released from the pulling means and worked into lasted position while thus held. Preferably the release of the upper is effected before the wipers become effective to wipe the upper over the last, thus avoiding such strain upon the margin of the upper at the toe end of the last as might result in tearing the material, particularly in a shoe made of felt, and also contributing to uniform lasting by rendering all portions of the margin of substantially equal tension at the time when the overwiping is effected. As far as I am aware the provision of means for causing the toe gripper to release the stock in such time relation to the operation of the wipers is new in a pulling-over and lasting machine.

A further feature of the invention comprises a novel construction of wiper operating mechanism including means dependent upon engagement with the shoe for effecting closing movement of the wipers. In the construction shown the wipers are caused to close during their movement lengthwise of

the shoe through the provision of an abutment which engages the end of the shoe and has the further function of holding the upper tensioned to permit the release of the toe 5 gripper, as hereinbefore explained.

Still another feature of the invention comprises novel mechanism for securing the upper in lasted position. For this purpose the machine shown is constructed to 10 drive tacks through the margin of the lasted upper and into the last. If an upper lasted as hereinbefore described is to be held effectively at the toe without loss of tension, it is desirable that fasteners be driven at the 15 outer sides of the pleats or folds formed in the margin of the material at the sides of the toe by the lateral inward movement of the wipers. In the use of comparatively thick stock, such as felt, the folds at the 20 edge of the stock frequently project upward to a considerable distance from the bottom of the last, and in order to insure that the fastener driving means, which is necessarily positioned in close relation to the bottom of 25 the last, shall not interfere with the proper gathering of the material and thus cause the fasteners to be driven in incorrect relation to the folds, the invention provides novel mechanism including fastener driving means 30 movable laterally inward at the outer sides of the folds in the stock into driving position in the correct relation to the folds, the wiper edges being slightly recessed to permit the tack fingers to be positioned far enough outward 35 to avoid interference with the folds. The construction shown provides laterally movable tackers with means connecting them to the wipers to cause them to be moved inward with the wipers.

40 The above as well as other features of the invention residing particularly in provision for relative adjustment of the wipers and for timing the operation of the wipers, and in certain details of construction and combinations of parts, will now be described with reference to the accompanying drawings and pointed out in the claims.

In the drawings,—

Fig. 1 is a view in side elevation and 50 partly in vertical section of the head portion of a machine including mechanism in which the invention is embodied;

Fig. 2 is a view in side elevation of the toe lasting and tacking mechanism;

55 Fig. 3 is an inverted plan view of the lasting mechanism;

Fig. 4 is a view in perspective of the mechanism shown in Fig. 2;

56 Figs. 5, 6 and 7 are plan views illustrating successive steps in the operation of the machine, and

Fig. 8 shows the forepart of a felt shoe the toe end of which has been pulled over and lasted by the use of the machine.

65 The machine in which the invention is

shown as embodied includes in its general organization many of the features shown and described in prior United States Letters Patent No. 1,135,950, granted on April 13, 1915, upon an application of R. F. McFeely, 70 certain of the features of this type of machine being described also in greater detail in a prior McFeely Patent No. 1,029,387, granted on June 11, 1912. In view of the disclosures in these prior patents the present description will be limited, as to the general organization of the machine, to such details as it is necessary to refer to for an understanding of the novel features of this invention. 80

Like the machine shown in said prior patents, the present machine includes a bottom rest 2 having a shoe engaging member 3 which engages the forepart of the shoe stock on the bottom of the last to position the work for the upper pulling operation, the member 3 being adjustable to determine the plane in which the bottom of the forepart of the shoe is presented. The machine has also a cam 4 on a cam shaft 6 for rocking the 85 bottom rest in a downward direction at the time of the upper pulling operation, a heel rest 8 which is moved upward into supporting engagement with the heel end of the shoe after the machine is started, and side 90 clamp arms 10 which are swung inward on opposite sides of the shoe into supporting and clamping engagement with the work after the upper pulling operation has been effected and before the operation of overlaying and securing the upper at the toe takes place. As distinguished from the machines shown in said prior patents, the present machine dispenses with all means for operating upon the stock at the sides of the shoe, the upper pulling means comprising a single toe gripper 12 arranged to engage a comparatively small extent of the margin of the upper at the end of the toe and operatively connected to an updraw lever 14. The lever 14 receives operative movement from a slide 16 operated by a cam 18 on the cam shaft 6, the connection between the slide and the lever comprising a spring 20 which is compressed to a greater or less extent in proportion to the resistance of the stock to cause the gripper 12 to pull the upper yielding. The gripper 12 is positioned initially as shown in Fig. 1 with the gripper jaws 22 in position to receive the edge of the upper 110 when the shoe is presented in engagement with the rest 2, the position of the gripper lengthwise of the last being determined by a slide 24 provided with a roll in engagement with the rear surface of the gripper bar to support it against the tension of a spring 26 which tends to swing the gripper rearwardly. 115

At the front of the gripper 12 the machine is provided with means for lasting the 130

toe end of the shoe and for driving tacks to secure the margin of the upper in lasted position. The lasting and tacking means is carried by a supporting arm 28 which is 5 swung toward and from the shoe about a center 29 by means of a slide bar 30 connected at its front end to the arm. The machine herein shown, like the machines shown in the prior patents above referred to, is 10 designed to perform its cycle of operations in successive steps between which the machine comes automatically to rest, but it should be understood that the invention is not limited to a machine having this particular characteristic. When the machine is 15 first started the gripper 12 is caused to engage and pull the upper, and the machine then comes to rest with the upper held under tension. Upon a subsequent actuation 20 of the starting treadle the side arms 10 are swung inward into supporting engagement with the shoe. When the treadle is depressed again the lasting and tacking mechanisms are operated to wipe the upper inward 25 over the bottom of the last and secure it in lasted position, after which the machine is caused to release the shoe and the parts are returned to their starting positions.

The lasting mechanism herein shown comprises wiper plates 32 which are mounted 30 on a wiper support 34 secured by means of a bolt 36 and a nut 38 to the lower end portion of the arm 28. A slot 40 in the support 34 permits the support to be adjusted 35 for advancing or retracting the lasting means relatively to the arm 28. The wipers 32 are positioned in overlapping relation and are provided in their adjacent faces with circular depressions 42 in order to 40 cause the operative edges of the wipers to be positioned in the same plane. The wipers are pivotally mounted for closing and opening movements upon a stud 44 on the support 34, this stud being located, as shown in 45 Fig. 7, at such a distance from the operative edges of the wipers that the wipers swing about an axis which is beyond the end face of the shoe when they are at the limit of their operative movement in order to cause 50 all portions of the wiper edges to receive a substantial component of movement laterally of the shoe during their movement lengthwise of the shoe. In order to cause the wipers to operate with effective pressure 55 at the sides of the toe part adjacent to the previously side-lasted portion of the shoe, for the purpose hereinbefore explained, the front end portions of the wipers on their shoe engaging side are beveled as shown at 60 45, and with the same object also the fore-part of the shoe is so positioned by the adjustable bottom rest relatively to the path of swinging movement of the wipers about the center 29 as to cause the ends of the wipers 65 to incline upward slightly from the plane

of the shoe bottom when they are at the end of their closing movement.

In the construction shown the wiper operating mechanism comprises means whereby the arm 28 in its movement toward the shoe is rendered effective to cause an operative closing movement of the wipers 32 during their bodily movement lengthwise of the shoe with the supporting arm. For this purpose there is mounted in a guideway in 75 the support 34 a slide 46 to which is secured by means of a bolt 48 a bar 50 provided on its forward end with a pad 52 for engagement with the toe end face of the shoe. The rear end of the slide 46 is arranged to engage the inner ends of a pair of levers 54 which are fulcrumed on studs 56 on the support 34 and are connected at their outer ends by means of links 58 to ears 60 which project from the outer sides of the wipers 32. 80 Springs 62 connected at their opposite ends respectively to the inner ends of the levers 54 and to pins on the support 34 tend to hold the levers in engagement with the slide 46 and to position the slide at its forward 85 limit of movement determined by engagement of the inner end of the bolt 48 in a slot 64 in the support 34. The parts are thus held normally by the springs 62 with the wipers in their open position. 90

The connections between the links 58 and the ears 60 comprise pins 66 which are carried by the links 58 and may be positioned in different holes 68 in the ears 60 to vary the normal spread or limit of movement of 100 the wipers 32 for shoes of different widths. In order to hold the pins 66 against accidental displacement while permitting them to be readily withdrawn when desired, the links 58 carry small springs 70 the ends of 105 which are positioned in recesses 72 in the links and are arranged to lie in annular grooves cut in the ends of the pins. 110

It will be understood that when the arm 28 is swung toward the shoe, carrying the wipers bodily in a direction lengthwise of the shoe, the pad 52 comes into engagement with the end of the shoe and stops the movement of the bar 50 and the slide 46 while the movement of the arm 28 and the wiper support 34 continues. Such continued movement of the wiper support causes the levers 54 to fulcrum about their points of engagement with the slide 46 and thus to swing the wipers 32 laterally over 115 the margin of the shoe during the continued bodily movement of the wipers lengthwise of the shoe. A slot 74 in the member 50 through which the bolt 48 extends permits this member to be adjusted 120 relatively to the slide 46 to vary the time in the movement of the arm 28 when the lateral closing movement of the wipers is to begin. For the purposes in view the forward end of the bar 50 is preferably posi- 125 130

tioned, as shown, in advance of the edges of the wipers to cause it to engage the shoe before the wipers have begun to advance over the margin of the shoe bottom. The 5 wipers thus begin to close inwardly toward the sides of the shoe prior to any overlaying movement at the toe end. As the arm 28 continues its movement after the pad 50 engages the shoe, it operates a tripping 10 device 76 on the toe gripper 12 and causes the gripper jaws to release the margin of the upper, as will be hereinafter more fully explained. In the construction herein shown the jaws of the gripper 12 have 15 smooth gripping faces, which is of particular advantage in effecting a quick release of stock such as felt which, if the jaws were corrugated, might tend to cling to them and thus prevent a prompt release.

20 For driving tacks to hold the margin of the upper in lasted position, the arm 28 carries tacking mechanism the construction of which includes many features embodied in mechanism shown and described in United 25 States Letters Patent No. 1,280,613 granted on Oct. 1, 1918, upon an application of Orrell Ashton. The machine herein shown is constructed to drive three tacks near the inner edge of the margin of the upper, the 30 tacks being fed through tubes 78 to tack holders 80 which are three in number and are mounted on tacker plates 82 carried by the arm 28. The central tacker plate 82 is fixed to the arm 28, and the two outside 35 plates 82 are mounted loosely on studs 84 on the arm. The openings in the two outside plates 82 through which the studs 84 extend are sufficiently large to permit lateral swinging movements of the plates. 40 Each of the outside plates rests at its upper end upon a nut 86 at the base of the stud 84 and rests at its lower rear corner upon the head of a bolt 88. A rod 90 extends through the two outside plates and 45 also loosely through the center plate 82 and carries a spring 92 which tends to press the two outside plates inwardly toward the center plate and to hold them in engagement with the shoulders 86 and the bolts 88. 50 Mounted on the two outside plates 82 are lugs 94 which carry studs 96 loosely engaged in openings in the wipers 32. As the wipers swing inwardly and outwardly they thus cause the two outside tacker plates 82 55 to rock about their points of engagement with the nuts 86 and the bolts 88, and the tack holders or fingers 80 which are carried by these plates are thus moved with the wipers and are maintained in position for 60 driving the tacks in predetermined relation to the edges of the wipers in any position of the wipers. It will be evident that the axis about which each of the plates 82 swings, represented by a line connecting the 65 nut 86 and the bolt 88, is inclined in such

relation to the plane of the shoe bottom that each side tack holder 80 approaches said plane as it swings inwardly.

For driving the tacks each of the tackers carries a driver rod 98 mounted in the plate 70 82, these rods being operated by a driver bar 100 mounted on the arm 28 with its upper end in position to be operated upon by a spring arm 102. The operation of the driver bar is controlled by the member 30 75 in a manner fully explained in the prior patents hereinbefore mentioned. The driver bar 100 is forked at its lower end, as shown in Fig. 4, and is extended backwardly into the spaces between the middle plate 82 and 80 the two outside plates, the extensions being provided with slots 104 (Fig. 2) for engagement with a transverse rod 106 which is connected to the middle driver rod 98 and extends loosely through slots formed in 85 blocks 108 mounted on the outside driver rods. By this arrangement all the driver rods may be operated together by the driver bar in all positions of the outside tackers 90 relatively to the middle tacker.

In the operation of the machine a shoe which has been previously prepared in the manner hereinbefore described, with a last inserted and its sides back of the toe in permanently lasted condition, is presented in 95 the position indicated by dotted lines in Fig. 1 with the portion of the shoe which extends over the bottom of the last in engagement with the bottom rest 2 and with a portion of the unsecured margin of the upper at the toe end of the last of comparatively narrow extent widthwise of the shoe extending within the open toe gripper jaws 22. Preferably also the upper of the shoe at the toe end is damped before the shoe is presented to the 100 machine. While holding the shoe in the position indicated the operator actuates the machine clutch, causing the toe gripper to close upon and pull the margin of the upper, the machine then coming to rest with the upper held under tension. If any adjustment of the upper material relatively to the last or any change in the tensioning of the upper is necessary, the operator is now afforded an opportunity to make such change as may be 105 required by manipulation of the gripper lever 14 in the usual manner.

The machine clutch is now actuated a second time, causing the side arms 10 to move inward into supporting and clamping engagement with the shoe. Upon a third actuation of the clutch the arm 28 is moved toward the shoe, the toe gripper at the same time being moved yieldingly backward by the action of the spring 26 to draw the intermediate portion of the margin of the upper over the bottom of the last. The wipers 32 follow the toe gripper, but before they arrive at the edge of the shoe the pad 52 comes into engagement with the upper at the end of the 110 115 120 125 130

toe, as shown in Fig. 5, and presses the upper against the last in such manner as to hold it substantially against relaxing when the toe gripper subsequently releases the margin. The wipers 32 now begin to close, and by the time they arrive at the edge of the shoe their wiping edges conform substantially to the lateral contour of the shoe, as shown in Fig. 6. At about this time and 5 before the wipers become effective to wipe the upper inward, the toe gripper is released by the tripping of the latch 76, the intermediate portion of the margin of the damped upper having been drawn backward 10 relatively to the portions at the corners of the last, as shown also in Fig. 6. During the continued inward movement of the arm 28 the wipers wipe the stock inward over the margin of the bottom of the last from the 15 sides simultaneously with their bodily movement lengthwise of the last to wipe the stock rearwardly from the toe end. By reason of the construction and arrangement of the wipers and their operating means hereinbefore particularly described, all portions of their wiping edges are moved in directions laterally of the shoe; and in consequence of this action, combined with the means for rendering the wipers effective with less pressure 20 on the stock at the sides than at the end of the toe, the unsecured margin at the sides of the toe is wiped inward directly from the side edges of the last without disarranging the previously side-lasted portion, and at the 25 same time the inner edge of the intermediate portion of the margin previously drawn backward by the gripper is gathered substantially between the free edges of the portion wiped inward from the sides. In the 30 shoe herein shown the marginal edges *c* of the upper are stitched by seams *b* along the sides of the shoe to an insertion *a* which may be of inferior material and which terminates back of the toe part of the shoe. In operating 35 upon this shoe the wipers, in their final position illustrated in Fig. 7, shape the stock in such manner as to leave the inner side edges *d* of the gathered material upstanding substantially in front of the ends of the 40 seams *b* and extending forwardly from these seams, while forming one or more backwardly extending folds *e* substantially between the portions *d*. When the wipers have been closed inward at the sides substantially as far as the seams *b*, as shown in 45 Fig. 7, tacks *f* are driven by the operation of the driver bar 100 to hold the stock in lasted position. It will be evident that since the two outside tack holders 80 are maintained in close relation to the edges of the wipers during the inward movement of the wipers, the folds in the margin of the stock 50 will be formed in advance of the side tackers and these tackers will be positioned finally to drive the tacks at the outer sides of the 55

upstanding side edges or folds *d* in locations substantially in line with the ends of the seams *b*, as indicated in Fig. 8, and another tack is driven in front of the intermediate gathered portion. After the tacks have been 70 driven the arm 28 is moved backward to carry the tackers and the wipers away from the shoe, the arms 10 are swung outwardly to release the shoe, and the different parts of the machine are returned to their starting 75 positions.

It will be evident that by the operation of the machine herein described the upper is stretched and shaped to the last at the toe uniformly at all portions of the toe and the 80 margin of the upper is molded down flat upon the bottom of the last to produce a smooth surface for the reception of the sole without any pronounced folds which might be accidentally cut at the time when the 85 upstanding gathered edge is trimmed off, and it will also be evident that the operation produces a lasted toe portion which merges smoothly with the previously side-lasted portion back of the toe. The uniformity of the work also results in the requirement of fewer tacks for holding the 90 margin in lasted position than have been required heretofore, and this not only saves tacks but also avoids the rapid wear of the 95 last which is the well known result of driving repeatedly a large number of tacks in this location.

While the invention is described herein with particular reference to the manufacture 100 of a felt shoe, it will be understood that the novel features are not limited in utility to the manufacture of this particular type of shoe nor, in the broader aspects of the invention, restricted to use upon shoes which 105 have been previously side-lasted.

The improvement in methods of making shoes herein disclosed is claimed in a separate application Serial No. 220,488 filed contemporaneously herewith.

Having described the invention, what I claim as new and desire to secure by Letters Patent of the United States is:

1. A machine for working over a last the toe portion of the upper of a shoe which has been previously side-lasted having, in combination, shoe positioning means, means for pulling the upper at the end of the toe only, overworking means, and operating mechanism constructed and arranged to cause said overworking means to work the toe portion of the upper inward over the bottom of the last continuously round the end and along the sides of the toe, said overworking means being so disposed relatively to the plane of the shoe bottom as to operate with less effective pressure on the stock at the side portions of the toe adjacent to the previously lasted portion of the shoe than at the end 120 of the toe.

2. A machine for working over a last the toe portion of the upper of a shoe which has been previously side-lasted having, in combination, shoe positioning means, end 5 lasting wipers, and means for operating said wipers to wipe the upper inwardly over the last round the toe, said wipers having their end portions so shaped relatively to other portions as to cause the wipers to operate with 10 less effective pressure on the stock at the side portions of the toe adjacent to the previously lasted portion of the shoe than at the end of the toe.
3. A machine for working over a last the 15 toe portion of an upper having, in combination, shoe positioning means, means for pulling the upper over the toe of the last, end lasting wipers, and operating mechanism constructed and arranged to cause the 20 wipers to work the margin of the upper inward over the bottom of the last uniformly round the end and along the sides of the toe with all portions of the wiping edges moving inward in directions transverse to 25 the longitudinal median line of the shoe, the shoe engaging faces of said wipers being disposed in such angular relation to the plane of the shoe bottom as to operate with less effective pressure on the stock at the 30 sides of the toe than at the end of the toe.
4. A machine for working over a last the toe portion of an upper having, in combination, end lasting wipers and operating mechanism constructed and arranged to cause the 35 wiping edges of the wipers to move laterally of the shoe at the end of the toe as well as at the sides of the toe, said wipers having portions of their shoe engaging faces inclined relatively to other portions of said 40 faces to cause the wipers to operate at the sides of the toe with less effective wiping pressure than at the end of the toe, and means for fastening the upper in overwiped position.
5. A machine for working over a last the 45 toe portion of an upper having, in combination, shoe positioning means, a pair of end lasting wipers constructed to present wiping edges extending continuously round the toe 50 of the shoe and mounted for movement about an axis located in front of the toe end of the shoe and at such a distance from their wiping edges as to give all portions of their wiping edges a substantial component of 55 movement laterally of the shoe, and means for operating said wipers to work the margin of the upper over the bottom of the last at the sides and the end of the toe, said wipers being shaped on their shoe engaging 60 faces to wipe the upper over the last at the sides of the toe with less effective pressure than at the end of the toe.
6. A machine for working over a last the toe portion of the upper of a shoe which 65 has been previously side-lasted having, in combination, shoe positioning means, a pair of end lasting wipers constructed to present wiping edges extending continuously round the toe, and means for operating said wipers to work the margin of the upper inward over the bottom of the last, said wipers having their overwiping 70 faces formed to operate with less effective wiping pressure at the sides of the toe adjacent to the previously lasted portion of the shoe than at the end of the toe.
7. A machine for working over a last the toe portion of an upper having, in combination, means for gripping the intermediate portion of the free edge of the upper at 75 the toe end of the shoe and pulling it back over the bottom of the last at an acute angle to the plane of the last bottom, end lasting wipers, and means for operating said wipers to work the unsecured margin of the upper 80 uniformly round the toe.
8. A machine for working over a last the toe portion of the upper of a shoe which has been previously side-lasted having, in combination, means for pulling the upper at the toe end of the last, and end lasting means 85 constructed and arranged to wipe the upper over the bottom of the last on a continuous line round the end and along the sides of the toe comprising wipers having their overwiping faces so disposed in relation to the 90 plane of the shoe bottom as to act with greater effective wiping pressure on the stock at the end of the toe than at the sides of the toe.
9. A machine for working over a last the 95 toe portion of the upper of a shoe which has been previously side-lasted having, in combination, shoe positioning means, means for pulling the upper at the toe end of the last, a pair of end lasting wipers constructed to 100 present wiping edges extending substantially continuously round the toe, and means for operating said wipers to work the margin of the upper inward over the bottom of the last, said wipers having their overwiping 105 faces formed to operate with less effective wiping pressure at the sides of the toe adjacent to the previously lasted portion of the shoe than at the end of the toe.
10. A machine for working over a last 110

the toe portion of the upper of a shoe which has been previously side-lasted having, in combination, shoe positioning means, a gripper for engaging substantially midway between the opposite sides of the toe end of the shoe a portion of the free edge of the upper of comparatively narrow extent widthwise of the shoe, means for operating said gripper to pull the upper and then to draw the gripped margin back over the bottom of the last, a pair of end lasting wipers constructed to present wiping edges extending substantially continuously round the toe of the shoe, and power driven means for operating said wipers with such components of movement lengthwise and laterally of the shoe as to wipe the margin of the upper inward at the sides of the toe uniformly with the previously lasted portion back of the toe and to gather the inner edge of the intermediate portion of the margin substantially between the edges of said inwardly wiped side portions.

11. A machine for working over a last the toe portion of the upper of a shoe which has been previously side-lasted having, in combination, shoe positioning means, a pair of end lasting wipers, means for operating said wipers with such components of movement lengthwise and laterally of the shoe as to work the unsecured margin of the upper inward over the bottom of the last round the end and along the sides of the toe to form at the sides upstanding folds directed forwardly from the previously lasted portion of the shoe, and means for driving a plurality of fasteners to secure the upper in lasted position including fasteners positioned between said side folds and the sides of the shoe.

12. A machine of the class described having, in combination, means for gripping at the toe end of a last a portion of an upper of comparatively narrow extent widthwise of the last, mechanism for operating said gripping means to stretch the upper and to carry the gripped portion inward over the bottom of the last, means for working the upper inward from opposite sides of the shoe to form in the margin upstanding folds directed lengthwise of the shoe toward the toe end at opposite sides of that portion of the margin initially acted upon by the gripping means, and means for securing the margin of the upper in lasted position.

13. A machine of the class described having, in combination, a gripper for engaging an upper at the toe end of a last, means for operating said gripper to pull the upper, end lasting wipers constructed to present wiping edges extending substantially continuously round the toe of the shoe, means for operating said wipers constructed to close them into substantial conformity to the contour of the shoe prior to their wiping

action on the stock and then to close them over the shoe substantially simultaneously at the end and the sides of the toe, and means arranged to be operated in time relation to the operation of said wipers for causing said gripper to release the upper when the wipers have been closed into conformity to the shoe and prior to their effective wiping action on the stock.

14. A machine of the class described having, in combination, a gripper for engaging an upper at the toe end of a last, means for operating said gripper to pull the upper, means for laying the margin of the upper over the bottom of the last, and means arranged to be operated in time relation to said overlaying means to cause the gripper to release the upper prior to the operation of said overlaying means on the shoe.

15. A machine of the class described having, in combination, a gripper for engaging an upper at the toe end of a last, means for operating said gripper to pull the upper, means for wiping the margin of the pulled upper over the bottom of the last, means for pressing the upper against the lateral periphery of the last to hold it under tension, means arranged to be operated in time relation to said wiping and holding means to cause the gripper to release the upper prior to the operation of the wiping means on the shoe, and means for fastening the upper in overwiped position.

16. A machine of the class described having, in combination, means comprising a toe gripper for pulling an upper at the toe end of a last, a pair of end lasting wipers constructed to present wiping edges extending substantially continuously round the toe of the shoe, means for moving said wipers toward the shoe, means for engaging the upper at the toe end of the last to hold it in tensioned condition, and means for causing said gripper to release the margin of the upper after said upper engaging means has engaged the shoe and prior to the operation of the wipers on the shoe.

17. A machine for working over a last the toe portion of the upper of a shoe which has been previously lasted and fastened by seams along the sides having, in combination, toe lasting wipers constructed to extend back into position to engage said seams, means for operating said wipers to last the toe portion of the shoe, and means arranged to be positioned by the wipers for inserting fastenings substantially in line with said seams to retain the toe portion of the upper in lasted position.

18. A machine for working over a last the toe portion of the upper of a shoe which has been previously lasted and fastened by seams at the sides having in combination, toe wiper mechanism, power operated means for operating said mechanism to last the toe, and

means movable laterally of the shoe into position for inserting fastenings substantially in line with the side seams to secure the toe portion of the upper in lasted position.

5 19. A machine for pulling over and lasting the toe of a shoe in which the upper has been previously stretched laterally and conformed to the last across the forepart at the rear of the toe having, in combination, up- 70

10 per pulling means confined to engagement with the upper at the toe end of the shoe for stretching the upper lengthwise without distorting the previously lasted portion at the rear of the toe, wipers movable lengthwise 75 and laterally of the shoe to gather and wipe inwardly the unlasted portion of the upper round the toe, and fastening devices arranged to be positioned laterally of the shoe by the movement of the wipers for fastening 15 the margin of the upper in lasted position.

20 20. A machine of the class described having, in combination, means comprising a toe gripper for pulling an upper at the toe end of a last, end lasting wipers, means for 80 moving said wipers toward the shoe, an abutment for engaging the upper at the toe end of the last, yielding means for causing said abutment to press upon the shoe with increasing pressure as the wipers move to- 85 ward the shoe, means for causing said gripper to release the upper while said abutment is in engagement with the shoe, and means for rendering said abutment effective to cause the wipers to close laterally over the 90 shoe during their movement lengthwise of the shoe.

25 21. In a machine of the class described, the combination with shoe positioning means, of a pair of end lasting wipers 95 mounted for relative closing and opening movements, means for effecting relative bodily movement of said wipers and the shoe in a direction lengthwise of the shoe, and means arranged to be rendered operative by en- 100 gagement with the shoe for causing the wipers to close during such relative bodily movement of the wipers and the shoe.

30 22. In a machine of the class described, the combination with shoe positioning 105 means, of a pair of end lasting wipers mounted for relative closing and opening movements, means for effecting relative bodily movement of said wipers and the shoe in a direction lengthwise of the shoe to cause 110 the wipers to wipe the margin of the upper over the bottom of the last at the extreme end of the shoe, and means arranged to be rendered operative by engagement with the shoe for causing the wipers to close laterally 115 over the shoe during said overwiping operation at the end of the shoe.

35 23. In a machine of the class described, the combination with shoe positioning 120 means, of a pair of end lasting wipers mounted for relative closing and opening

movements laterally of the shoe, means for effecting relative bodily movement of said wipers and the shoe in a direction lengthwise of the shoe, an abutment arranged to engage the end face of the shoe, and operat- 70

ing mechanism between said abutment and the wipers to cause the wipers to be closed over the shoe by said relative bodily movement of the wipers and the shoe after the abutment has engaged the shoe. 75

24. In a machine of the class described, the combination with shoe positioning means, of a pair of end lasting wipers mounted for relative closing and opening movements, means for effecting relative bodily 80 movement of said wipers and the shoe in a direction lengthwise of the shoe, levers connected to said wipers to operate them, and means arranged for operation by engage- 85

ment with the shoe to render said levers effective to close the wipers over the shoe during said relative bodily movement of the wipers and the shoe.

25. In a machine of the class described, the combination with shoe positioning 90 means, of a wiper support mounted for movement lengthwise of the shoe, a pair of end lasting wipers mounted on said support for relative closing and opening movements, a pair of operating members mounted on 95 said support independently of the wipers and connected to the wipers, and means ar- ranged for operation upon engagement with the end of the shoe to render said operating members effective to close the wipers through 100 the movement of the wiper support and the wipers lengthwise of the shoe.

26. In a machine of the class described, the combination with shoe positioning means, of a wiper support, a pair of end 105 lasting wipers mounted on said support for relative closing and opening movements, a pair of levers mounted on said support independently of the wipers, means connecting said levers to the wipers, and means con- 110 structed to provide an abutment between the end of the shoe and said levers to render the levers effective to close the wipers through relative movement of the wiper support and the shoe.

27. In a machine of the class described, the combination with shoe positioning means, of a wiper support, a pair of end lasting wipers mounted on said support for relative closing and opening movements, a 120 pair of levers pivoted on said support, links connecting the levers to the wipers, and means constructed to provide an abutment between end of the shoe and said levers to render the levers effective to close the wipers 125 through relative movement of the wiper support and the shoe.

28. In a machine of the class described, the combination with shoe positioning means, of a wiper support, a pair of end 130

lasting wipers mounted on said support for relative closing and opening movements, a pair of levers pivoted on said support, links connecting the outer ends of said levers to the wipers, and a slide mounted on said support and provided with means for engaging the end face of the shoe, said slide being arranged in operative relation to the inner ends of said levers to render the levers effective to close the wipers through relative movement of the wiper support and the shoe.

29. In a machine of the class described, the combination with shoe positioning means, of a wiper support, a pair of end lasting wipers mounted on said support for relative closing and opening movements, a pair of levers pivoted on said support and connected to the wipers, a slide mounted on said support and arranged to provide an abutment between said levers and the end face of the shoe for rendering the levers effective to close the wipers upon relative movement of the wiper support and the shoe, and spring means tending to move said slide relatively to the wiper support in the direction of the shoe.

30. In a machine of the class described, the combination with shoe positioning means, of a wiper support, a pair of end lasting wipers mounted on said support for relative closing and opening movements, a pair of levers pivoted on said support and connected to the wipers, a slide mounted on said support and arranged to provide an abutment between the inner ends of said levers and the end face of the shoe to render the levers effective to close the wipers upon relative movement of the wiper support and the shoe, and spring means tending to operate said levers to open the wipers and to force said slide forwardly toward the shoe.

31. In a machine of the class described, the combination with shoe positioning means, of a wiper support mounted for movement lengthwise of a shoe positioned by said means, a pair of end lasting wipers mounted on said support for relative closing and opening movements, and means arranged to be rendered operative by engaging means with the shoe for closing the wipers during the movement of the support and the wipers lengthwise of the shoe.

32. In a machine of the class described, the combination with shoe positioning means, of a wiper support mounted for movement toward and from a shoe positioned by said means, a pair of end lasting wipers mounted on said support for relative closing and opening movements, operating members carried by said support and connected to the wipers, and an abutment arranged to engage the end face of the shoe and to render said operating members effective to close the wipers during continued movement of the support and wipers toward the shoe.

33. In a machine of the class described, the combination with shoe positioning means, of a wiper support mounted for movement toward and from a shoe positioned by said means, a pair of end lasting wipers mounted on said support for relative closing and opening movements, levers pivoted on said support and connected to the wipers, and an abutment arranged to engage the end face of the shoe and to provide a fulcrum for the levers to cause the levers to close the wipers during continued movement of the support toward the shoe.

34. In a machine of the class described, the combination with shoe positioning means, of a wiper support mounted for movement toward and from a shoe positioned by said means, a pair of end lasting wipers mounted on said support for relative closing and opening movements, levers pivoted on said support and connected to the wipers, and a slide mounted on said support and arranged to provide an abutment between the shoe and said levers to cause the levers to operate the wipers during continued movement of the support toward the shoe.

35. In a machine of the class described, the combination with shoe positioning means, of a wiper support, a pair of end lasting wipers mounted on said support for relative closing and opening movements, operating members for said wipers, shoe engaging means arranged to render said members effective to operate the wipers upon relative movement of the wiper support and the shoe, and means adjustably connecting said members and the wipers for varying the spread of the wipers for shoes of different widths.

36. In a machine of the class described, the combination with shoe positioning means, of a wiper support, a pair of end lasting wipers mounted on said support for relative closing and opening movements, levers for operating the respective wipers, shoe engaging means arranged to render said levers effective to close the wipers upon relative movement of said wiper support and the shoe, and links adjustably connecting said levers to the wipers.

37. In a machine of the class described, the combination with shoe positioning means, of a pair of end lasting wipers mounted for relative closing and opening movements and constructed to present wiping edges extending substantially continuously round the end of the shoe, means for effecting relative bodily movement of said wipers and a shoe positioned by said means in a direction lengthwise of the shoe, an abutment arranged to engage the end face of the shoe, connections between said abutment and the wipers to cause the wipers to be closed over the shoe, and means for posi-

tioning said abutment normally in advance of the intermediate portion of the wiping edges of the wipers to cause the closing movement of the wipers to begin before said intermediate portion of the wiping edges becomes effective to wipe the stock over the bottom of the last.

38. In a machine of the class described, the combination with shoe positioning means, of a wiper support, a pair of end lasting wipers mounted on said support for relative closing and opening movements and constructed to present wiping edges extending substantially continuously round the end of the shoe, wiper operating means comprising a member mounted on said support for engagement with the end face of a shoe positioned by said means, and yieldable means for positioning said member normally with its shoe engaging portion in front of the intermediate portion of the wiping edges of the wipers.

39. In a machine of the class described, the combination with shoe positioning means, of a pair of end lasting wipers mounted for relative closing and opening movements laterally of a shoe positioned by said means and constructed to present wiping edges extending substantially continuously round the end of the shoe, means for effecting relative bodily movement of said wipers and the shoe in a direction lengthwise of the shoe to wipe the stock over the bottom of the last at the extreme end of the shoe, and means for initiating the closing movement of the wipers before they become effective upon the stock at the end of the shoe.

40. In a machine for lasting the toe portion of a felt shoe, the combination with shoe positioning means, of a pair of end lasting wipers mounted for movement lengthwise of the shoe and for relative movement laterally of the toe end of the shoe to wipe and gather the margin of the upper stock inwardly toward the middle of the toe, and tackers arranged relatively to the wipers to drive tacks through the margin of the stock in locations between the sides of the shoe and the gathered portion, said tackers being mounted for movement lengthwise and laterally of the shoe with the wipers with the portions of the tackers which are adjacent to the shoe positioned continuously at the outer side of the free inner edge of the margin of the upper.

41. In a machine for lasting the toe portion of a felt shoe, the combination with shoe positioning means, of toe embracing wipers mounted for relative movement laterally of the toe end of the shoe to wipe and gather the margin of the upper stock round the toe inwardly toward the middle of the toe, and upper securing means comprising a

middle tacker and two side tackers, movable lengthwise of the shoe to operative position, said side tackers being mounted for movement inwardly with the wipers toward the middle tacker with the portions of said side tackers which are adjacent to the shoe positioned continuously at the outer side of the free inner edge of the margin of the upper.

42. In a machine of the class described, the combination with shoe positioning means, of a support movable lengthwise of a shoe positioned by said means, end lasting wipers carried by said support, tackers mounted on the support independently of the wipers, means for closing said wipers laterally over the shoe, and means connecting the tackers to the wipers to cause the tackers to be moved inwardly over the shoe by the wipers.

43. In a machine of the class described, the combination with shoe positioning means, of a pair of end lasting wipers mounted for relative closing and opening movements laterally of a shoe positioned by said means, means for effecting relative movement of said wipers and the shoe in a direction lengthwise of the shoe, means arranged to be operated by engagement with the end face of the shoe to cause said wipers to close during said relative movement, and tackers connected to said wipers for movement laterally of the shoe with the wipers.

44. In a machine of the class described, the combination with shoe positioning means, of end lasting wipers mounted for relative closing and opening movements laterally of a shoe positioned by said means, means for closing the wipers, tackers mounted independently of the wipers and movable also laterally of the shoe into and out of tack driving position, and connections extending from said tackers to the wipers to cause the tackers to be moved inward with the wipers.

45. In a machine of the class described, the combination with shoe positioning means, of end lasting wipers mounted for relative closing and opening movements laterally of a shoe positioned by said means, means for closing said wipers, end tackers movable also laterally of the shoe into and out of tack driving position, means connecting the tackers and the wipers to cause the tackers to be moved with the wipers, tack drivers for the several tackers, a driver bar, and means connecting said bar to the drivers constructed to maintain operative connection between the bar and the drivers in all positions of the tackers and the wipers.

46. In a machine of the class described, the combination with shoe positioning means, of a pair of end lasting wipers constructed to present wiping edges extending continuously round the toe of a shoe positioned by said means and mounted for movement about an axis in front of the toe end.

of the shoe and at a distance from their wiping edges to give all portions of their wiping edges a movement laterally of the shoe, said wipers being constructed and arranged 5 to wipe the upper over the last at the sides of the toe with less effective pressure than at the end of the toe, means for operating said wipers, and upper fastening instrumentalities connected to said wipers for 10 movement laterally of the shoe into fastener driving position.

47. In a machine of the class described, the combination with last and upper positioning means, of a pair of end embracing wipers, and power means for moving said wipers lengthwise of the shoe and for closing them inward laterally of the shoe to wipe the margin of the upper over the bottom of the last round the end and along the opposite 15 sides of the end portion of the shoe, said wipers being mounted to swing relatively about an axis positioned substantially midway between the opposite sides of the shoe and beyond the end face of the shoe when the wipers are at the end of their operative movement, and said wipers being shaped and arranged relatively to the plane of the shoe bottom to apply less pressure upon the upper at the sides of the end portion 20 of the shoe than at the extreme end of the shoe.

48. In a machine of the class described, the combination with last and upper positioning means, of means for gripping and pulling the margin of the upper at the toe end of the last, end embracing wipers having wiping edges constructed and arranged to extend substantially continuously round the end of the shoe, means for operating 35 said wipers to cause their edges to engage the upper substantially along the edge of the shoe bottom round the end of the shoe and then to wipe the upper inward over the bottom of the last, and means for causing said gripping means to release the margin of the upper when said wipers have arrived substantially in embracing relation to the upper along the edge of the shoe bottom and before they become effective to 40 wipe the upper inward.

49. In a machine of the class described, the combination with last and upper positioning means, of means for gripping and pulling the upper at the toe end of the last, end embracing wipers, means for moving 55 said wipers lengthwise of the shoe, means for engaging the end face of the shoe to retain the upper in its tensioned condition, means for rendering said shoe engaging 60 means effective to cause the wipers to close inward into substantial conformity to the contour of the edge of the shoe bottom and then to wipe the upper inward laterally of the shoe during their continued movement lengthwise of the shoe, and means for caus- 65

ing said gripping means to release the upper when said wipers have closed into substantial conformity to the edge of the shoe bottom and before they become effective to wipe the upper inward.

50. In a machine of the class described, the combination with shoe positioning means, of end embracing wipers mounted for movement lengthwise of the shoe, said wipers being pivoted for swinging movement about an axis positioned substantially midway between the opposite sides of the shoe and beyond the end face of the shoe when the wipers are at the limit of their operative movement, an abutment arranged to 70 engage the end face of the shoe, and means for rendering said abutment effective to cause the wipers to swing about said axis as they move lengthwise of the shoe.

51. In a machine of the class described, the combination with shoe positioning means, of end embracing wipers mounted to swing about an axis substantially midway between the opposite sides of the shoe, means for moving said wipers lengthwise 75 of the shoe, an abutment arranged to engage the end face of the shoe, and means for rendering said abutment effective to cause the wipers to be swung about said axis as they are moved lengthwise of the 80 shoe.

52. In a machine of the class described, the combination with shoe positioning means, of end embracing wipers mounted for movement together lengthwise of the shoe and also for relative movement laterally of the shoe, upper fastening means comprising a middle tacker and other tackers at opposite sides of said middle tacker, said tackers being movable lengthwise of the shoe with 100 the wipers, and means for causing said side tackers to receive positioning movement laterally of the shoe with the wipers while the middle tacker is restrained from movement 105 laterally of the shoe.

53. In a machine of the class described, the combination with shoe positioning means, of end embracing wipers mounted for movement lengthwise of the shoe and also for relative closing and opening movements laterally of the shoe, upper fastening means comprising a middle tacker and opposite side tackers movable lengthwise of the shoe with said wipers, means for maintaining said middle tacker stationary against movement laterally of the shoe, and connections between the wipers and said side tackers for moving said tackers with the wipers laterally of the shoe and relatively to the middle tacker.

54. In a machine of the class described, the combination with shoe positioning means, of a wiper support mounted for movement lengthwise of the shoe, end embracing wipers mounted on said support for 115 120 125 130

- relative closing and opening movements laterally of the shoe, an abutment movably mounted on said support in position to engage the end of the shoe, and connections 65
- 5 between said abutment and the wipers for closing the wipers inward laterally of the shoe through the movement of the wiper support and the wipers lengthwise of the shoe.
- 10 55. A machine for pulling over and lasting the toe of a shoe in which the upper has been previously stretched laterally and conformed to the last across the forepart at the rear of the toe having, in combination, upper pulling means confined to engagement 70
- 15 with the upper at the toe end of the shoe for stretching the upper lengthwise without distorting the previously lasted portion at the rear of the toe, and wipers mounted to 75
- 20 swing laterally of the shoe in substantially continuous engagement with the upper about the toe from one side of the toe to the other to operate with both a gathering and an over-wiping effect on all portions of the 80
- 25 length of the unlasted margin of the upper round the toe to gather the margin uniformly in front of the previously lasted portion. 85
56. A machine for pulling over and lasting the toe of a shoe in which the upper has been previously stretched laterally and conformed to the last across the forepart at the rear of the toe having, in combination, upper pulling means confined to engagement 90
- 30 with the upper at the end of the toe for stretching the upper lengthwise without distorting the previously lasted portion at the rear of the toe, and means for gathering and wiping the unlasted portion of the upper in- 95
- 35 wardly in front of the previously lasted portion comprising a pair of end embracing wiper plates constructed and arranged for substantially continuous engagement with the upper round the toe from one side of 100
- 40 the toe to the other and mounted to swing each about an axis substantially midway between the opposite sides of the toe. 105
57. A machine for pulling over and lasting the toe of a shoe in which the upper has 110
- 45 been previously stretched laterally and conformed to the last across the forepart at the rear of the toe having, in combination, upper pulling means confined to engagement with the upper at the toe end of the shoe for stretching the upper lengthwise without distorting the previously lasted portion at the rear of the toe, and embracing wipers comprising a pair of wiper plates arranged to be moved lengthwise and laterally of the shoe simultaneously to gather and wipe the unlasted portion of the upper inwardly in front of the previously lasted portion, and power driven operating mechanism for said upper pulling means and 115
- wipers automatically controlled to come to a stop at the end of the upper pulling operation and again at the end of the toe lasting operation. 120
58. A machine for pulling over and lasting the toe of a shoe in which the upper has been previously stretched laterally and conformed to the last across the forepart at the rear of the toe having, in combination, upper pulling means confined to engagement with the upper at the end of the toe for stretching the upper lengthwise without distorting the previously lasted portion at the rear of the toe, a wiper support movable lengthwise of the shoe, wipers carried by 125
- said support and mounted for closing movements laterally of the shoe, and upper fastening devices also carried by said wiper support and comprising tackers connected to the wipers for positioning movements laterally of the shoe with the wipers. 130
59. A machine for lasting the toe of a shoe which has been previously side-lasting having, in combination, shoe positioning means, means for pulling the upper at the end of the toe only, end embracing wipers arranged to extend continuously round the toe end of the shoe and movable in such relation to the shoe as to impart to all portions of their wiping edges a component of movement laterally of the shoe, and means for operating said wipers to gather and wipe the margin of the upper inwardly round the end and along the sides of the toe. 135
60. In a machine of the class described, the combination with shoe positioning means, of means for wiping the upper into lasted position about the toe of the shoe, and upper fastening means comprising tackers mounted for positioning movements laterally of the toe end of the shoe about axes inclined to the plane of the shoe bottom. 140
61. In a machine of the class described, the combination with shoe positioning means, of end embracing wipers mounted for closing movement laterally of the shoe, means for closing said wipers inwardly over the shoe, and upper fastening means comprising tackers connected to the wipers to be moved inwardly by the wipers into position for driving the tacks, said tackers being mounted to move inwardly about axes so inclined relatively to the plane of the shoe bottom as to cause them to approach said plane in their inward movement. 145
62. In a machine of the class described, the combination with means for working an upper over the toe end of a last, of upper fastening means comprising a support movable lengthwise of the shoe and tackers carried by said support and mounted for positioning movements laterally of the shoe, and a device carried by said support and operative through engagement with the end 150

face of the shoe to impart to said tackers their positioning movements laterally of the shoe.

63. In a machine of the class described, 5 the combination with means for pulling an upper over the toe end of a last, of a front arm mounted to swing lengthwise of the shoe, wipers carried by said arm and mounted for closing movements laterally of the shoe, and a 10 wiper closing device carried by said arm and operative through engagement with the end face of the shoe to impart closing movements to the wipers during their movement lengthwise of the shoe.

- 15 64. In a machine of the class described,

the combination with means for pulling an upper over the toe of a last, of a front arm mounted for swinging movement lengthwise of the shoe, end embracing wipers carried by said arm, means automatically operative 20 in the swinging movement of said arm to close the wipers inward laterally of the shoe, and upper fastening means comprising tackers carried by said arm and connected to the wipers to be positioned laterally of the 25 shoe by the closing movement of the wipers.

In testimony whereof I have signed my name to this specification.

BERNHARDT JORGENSEN.

Certificate of Correction.

It is hereby certified that in Letters Patent No. 1,413,589, granted April 25, 1922, upon the application of Bernhardt Jorgensen, of Beverly, Massachusetts, for an improvement in "Machines for Working Uppers Over Lasts," errors appear in the printed specification requiring correction as follows: Page 10, line 50, claim 31, for the word "means" insert the syllable *ment*; page 11, line 69, claim 41, before the word "inwardly" insert the word *also*; and that the said Letters Patent should be read with these corrections therein that the same may conform to the record of the case in the Patent Office.

Signed and sealed this 17th day of October, A. D., 1922.

[SEAL.]

KARL FENNING,

Assistant Commissioner of Patents.
